(57) **CLAIM**

An ornamental design for a disk drive with Morse code patterned sleeve, as shown and described.

DESCRIPTION

FIG. 1 is a perspective view of a disk drive with Morse code patterned sleeve showing my new design;

FIG. 2 is a front view thereof;

FIG. 3 is a side view thereof;

FIG. 4 is an opposing side view thereof;

FIG. 5 is a back view thereof;

FIG. 6 is a top view thereof;

FIG. 7 is a bottom view thereof; and,

FIG. 8 is another perspective view thereof, wherein the swivel connector is rotated in a downward position.

The broken line showing of the swivel connector is included for the purpose of illustrating environmental structure and forms no part of the claimed design.
